DESIGN FOR A RIBBED LINING PLATE FOR KNIVES

Arthur H. Pneuman, Bradford, Pa.

Application October 8, 1934, Serial No. 53,747

Term of patent 14 years

To all whom it may concern:

Be it known that I, Arthur H. Pneuman, a citizen of the United States, residing at Bradford, in the county of McKean and State of Pennsylvania, have invented a new, original, and ornamental Design for a Ribbed Lining Plate for Knives, of which the following is a specification, reference being had to the accompanying drawing, forming a part thereof.

Figure 1 shows a perspective view of a single lining plate illustrating my design. Fig. 2 is an illustrative cross section of a lining plate as on line 2—2, Fig. 1, and showing clearly the particular shape of the raised rib.

What I claim is:

The ornamental design for a ribbed lining plate for knives, as shown and described.

ARTHUR H. PNEUMAN.
